INTERCOMMUNICATING UNIT

James D. Floria, Fox Point, Wis., assignor to Webster Electric Company, Racine, Wis., a corporation of Delaware

Application November 29, 1957, Serial No. 48,720

Term of patent 14 years

(Cl. D26—14)

Figure 1 is a perspective view of an intercommunicating unit embodying my new design; and

Figure 2 is an end view of the unit upon a reduced scale and partly broken away to show the molding on the upper rear section.

The essential features of the intercommunicating unit resides in the portion shown in solid lines. The broken line portion in Figure 1 indicating ancillary switch structure is for illustration only. The rear of the unit is conventional comprising merely a flat panel.

I claim:

The ornamental design for an intercommunicating unit, substantially as shown and described.
